ROOF FOR TOY STRUCTURES

Filed Aug. 22, 1930

INVENTOR,

ARTHUR P. CHURCH.

BY *Donald H. Lipincott*

ATTORNEY.

UNITED STATES PATENT OFFICE

ARTHUR P. CHURCH, OF SANTA BARBARA, CALIFORNIA

ROOF FOR TOY STRUCTURES

Application filed August 22, 1930. Serial No. 477,053.

My invention relates to sectional roof structures, and particularly to such structures as adapted to structural toys.

Among the objects of my invention are: 5 To provide a roof structure which is pleasing in appearance, and simulates a full size roof; to provide a structure which is adaptable to roofs of any size; to provide a structure which is weatherproof and will afford 10 actual protection to outdoor toy buildings; to provide a structure which is easily erected; and to provide a structure which is durable and is readily manufactured.

Other objects of my invention will be apparent or will be specifically pointed out in 15 the description forming a part of this specification, but I do not limit myself to the embodiment of my invention herein described, as various forms may be adopted within the 20 scope of the claims.

Referring to the drawing:

Figure 1 is a perspective view of a portion of the gable of a toy building, and showing 25 a ridge section and two side sections of a roof, built in accordance with my invention, in cross section.

Figure 2 is a perspective view showing the under side of a ridge section of the roof structure.

Figure 3 is a similar view showing the under side of a side section.

Figure 4 is a detailed view showing the method of attaching the covering material of the roof to a rigid base-plate.

In general terms, the roof structure of my 35 invention comprises a plurality of sections, each of said sections being formed from a substantially rigid base-plate having means on opposite edges thereof for attaching succeeding sections, and a covering material secured to each of the base-plates and overlapping the junction with the succeeding section. The covering material should possess a certain degree of flexibility, but a wide 40 choice is available in its selection, artificial leather, genuine leather, paper products, or celluloid, all being usable for this purpose.

In the preferred form of invention illustrated in the drawing, a portion of a wall 45 10 of a toy structure is shown, carrying a

truss comprising a cross-member 11 and a pair of diagonal roof beams 12 whose adjacent ends are held by a fitting 13 which supports a ridgepole 15.

A sufficient number of such trusses or other suitable structures are used satisfactorily to support the roof.

Two different types of roof section are preferably used, different somewhat in function but not in principle. The ridge sections 60 comprise a base-plate 16, preferably formed of a substantially rigid material such as sheet metal. The base-plate is bent along its central line to conform with the desired angle or pitch of the roof which it is wished to 65 build.

Each of the lower edges of the ridge section is provided with means for attaching an adjacent section. This means preferably comprises a recurved hook 17 formed by bending the edge of the material outward and back upon itself. A suitable covering material 18 is secured over the top of the base-plate and overlapping its recurved edges. I have found that a satisfactory material for 70 this cover is imitation leather, i. e., a fabric having a surface treated to simulate leather. This material is durable, may be obtained in many pleasing shades, and is substantially 75 waterproof, so that structures formed there- 80 of may be left in the rain without injury. Other materials such as untreated fabric, tough paper, or oilcloth, may also be used if desired.

The covering of the ridge section is pref- 85 erably attached in a manner which does not require that the material be punctured. A satisfactory method is to form the base-plate 16 with a plurality of openings 20 adjacent the bend which forms the ridge. Notches 21 may also be formed at the ends of the ridge bend. A strip of fabric 22 is adhesively applied to the under side of the base-plate, the holes 20 and notches 21 allowing the strip to be secured directly to the covering material 18. A much more permanent 90 fastening is secured by this method than is possible if it be attempted to secure the covering material adhesively directly to the 95 base-plate. 100

The side sections are formed as shown in Figure 3, each comprising a base-plate 25 formed with the oppositely recurved hooked edges 26 and 27. A piece of covering material 28 is secured to the base-plate between the edges, and overlying the upwardly recurved edge 27. Since the covering material of these sections may be punctured, adjacent its upper edges, without in any way harming the structure, the simpler method of fastening the covering material shown in Figure 4 is preferred. Tongues 30, preferably of sharp triangular form, are struck up from the base-plate, leaving the triangular opening 31 therein. These tongues are forced through the covering material 28 and clinched down on the upper side as shown, holding the material firmly against the base-plate.

In constructing the roof, the ridge sections 20 are simply laid over the ridgepole, and the lower sections are attached thereto, the downwardly curved hook edges 26 of the lower sections engaging the upwardly hooked edges 17 of the ridge sections. The 25 extended edges of the covering material on the roof sections overlie the point of attachment of the lower sections, covering the perforations formed by the tongues 30. Additional sections may be hooked on as desired 30 to obtain as extensive a roof as is necessary for the building to be constructed. The roof thus formed is substantially self-supporting. It is possible to lift a ridge section and a large number of lower sections off of the 35 structure together, without dis-assembling the entire roof, which is an advantage in toy structures. The roof has sufficient weight to maintain itself in position, and the overlapping strips of covering material form a roof which is actually weather tight.

I claim:

1. A roof structure comprising a plurality of plates, means on each plate for attaching a succeeding plate, and a cover secured to each plate and extending to overlie its junction with the succeeding plate.
2. A roof section comprising a substantially rigid plate, means on opposite edges of said plate for joining other sections thereto, and a cover secured to the plate between said edges and overlapping one of said edges to conceal the junction with the succeeding section.
3. A roof section comprising a substantially rigid plate having opposite edges recurved to form hooks for attaching succeeding sections, and a cover secured to the plate between said edges and overlapping one of said edges to conceal the junction with the succeeding section.
4. A roof section comprising a substantially rigid plate, means adjacent a lower edge of said plate for attaching a succeeding plate, and a flexible cover secured to said

plate and overlapping said edge to conceal the junction with the succeeding section.

5. A roof section comprising a substantially rigid plane, an upwardly recurved hook formed on the lower edge of said plate 70 for attaching a succeeding section, and a flexible cover attached adjacent the center of said plate and overlapping said hook.

6. A roof section comprising a substantially rigid plate having oppositely recurved 75 hooks formed on opposite edges thereof, and a flexible cover attached between said edges and overlapping the upturned portion of one of said hooks.

7. A ridge section for a roof comprising 80 a substantially rigid plate bent longitudinally to conform to the desired roof angle, means adjacent the lower edges of said plate for attaching succeeding sections thereto, and a flexible cover attached centrally of said 85 plate and overlapping each of said lower edges.

In testimony whereof, I have hereunto set my hand.
